ALEXANDER MARTINEK, OF WORCESTER, MASSACHUSETTS, ASSIGNOR TO PRAGER CO., INC., A CORPORATION OF NEW YORK

DESIGN FOR WALL PAPER OR SIMILAR MATERIAL

Application filed March 17, 1930. Serial No. 34,914. Term of patent 3½ years.

To all whom it may concern:

Be it known that I, ALEXANDER MARTINEK, a citizen of the United States, and resident of Worcester, in the county of Worcester and State of Massachusetts, have invented a new, original, and ornamental Design for Wall Paper or Similar Material, of which the following is a specification.

In the accompanying drawing:—

The figure is a surface view of a piece of wall paper or similar material showing the design. The area within the dot and dash lines indicates one complete unit of the design. Outside of the dot and dash lines frag-

mentary portions of repeat units have been shown arranged around said complete unit so that the angle of the complete unit designated by letter A corresponds with the angle B of a repeat directly below the complete unit, and so that all units are adjacent each other and in horizontal adjacent lines.

I claim:—

The ornamental design for wall paper or similar material as shown and described.

Signed at New York in the county of New York and State of New York this 1st day of March A. D. 1930.

ALEXANDER MARTINEK.
